UNITED STATES PATENT OFFICE.

WILSON D. CRAIG WRIGHT, OF PHILADELPHIA, PENNSYLVANIA, ASSIGNOR OF ONE-HALF TO JOSEPH WRIGHT, OF PHILADELPHIA, PENNSYLVANIA.

ATOMIZING AND MIXING VALVE.

1,078,816.

Specification of Letters Patent.

Patented Nov. 18, 1913.

Application filed June 3, 1912. Serial No. 701,123.

To all whom it may concern:

Be it known that I, WILSON D. CRAIG WRIGHT, a citizen of the United States, residing at Philadelphia, in the county of Philadelphia and State of Pennsylvania, have invented certain new and useful Improvements in Atomizing and Mixing Valves; and I do hereby declare the following to be a full, clear, and exact description 10 of the invention, such as will enable others skilled in the art to which it appertains to make and use the same, reference being had to the accompanying drawings, and to characters of reference marked thereon, which 15 form a part of this specification.

The present invention has reference, generally, to improvements in delivery or atomizing valve-mechanism for introducing fuel to the cylinder of an internal combustion engine.

The invention has for its principal object to provide a simple, effective and clean delivery or atomizing valve-mechanism for delivering and intermixing various fuel-elements 25 comprising heavy hydrocarbons, including the natural crude mineral oils of paraffin or asphalt base, as well as kerosene and other manufactured or modified products of the same general class, and air and 30 water, to provide a fuel-mixture from the combustion of which power may be produced substantially after the method indicated in previously granted Letters-Patent No. 832,728, dated October 9, 1906.

A further object of the present invention is to provide a valve-construction, for the purpose above indicated, which is subject to accurate mechanical control; which is adapted to thoroughly intermix the fuel-elements; 40 which is constructed to prevent leakage caused by back-pressure; and which is arranged to obviate choking of its fuel-passages by the collection of dirt, or foreign elements.

Other objects of the present invention not at this time more particularly enumerated will be clearly understood from the following detailed description of my present invention.

With the various objects of the present invention in view, the same consists, primarily, in the novel construction of atomizing and mixing valve-mechanism for internal combustion engines hereinafter set forth; 55 and, furthermore, this invention consists in

the several novel arrangements and combinations of the various devices and parts, as well as in the details of the construction thereof, all of which will be hereinafter more fully described in the following specification and then finally embodied in the clauses of the claim which are appended to and which form an essential part of this specification.

The invention is clearly illustrated in the accompanying drawings, in which:—

Figure 1 is a detail sectional representation of the novel construction of atomizing and mixing valve-mechanism in its operative connection with the cylinder of an internal construction engine, the same being made according to and embodying the principles of the present invention. Fig. 2 is a similar detail sectional view illustrating certain movable portions of the valve-mechanism in their open or operative position. Fig. 3 is a transverse section taken on line 3—3 in said Fig. 2, and looking in the direction of the arrow *x*. Fig. 4 is another detail transverse section taken on line 4—4 in said Fig. 2, looking in the direction of the arrow *y*.

Similar characters of reference are employed in all of the herein-above described views, to indicate corresponding parts.

The novel atomizing and mixing valve-mechanism comprising my present invention is designed to mix, atomize, and deliver to the engine-cylinder a hydrocarbon fuel comprising three elements, viz., a heavy hydrocarbon, water and air. The general theory of the intermixing or vaporizing of the said fuel-elements to produce a combustible fuel is described in former United States Letters-Patent No. 832,728 of October 9th, 1906, and consists in bringing together heavy hydrocarbon oil and water, the water taking the form of minute drops or globules and the oil being carried on these drops or globules in the form of a very thin film or coating, the air tending to further break up and atomize this union of oil and water, and also provide oxygen to the combustion of the gaseous mixture produced by such intermixing of the fuel-elements, whereby, in this manner it is possible to use, in the production of a suitable gaseous fuel for hydrocarbon or internal combustion engines, a hydrocarbon of very low or heavy grade, which without assistance would not be capa-

ble of the fine subdivision or atomizing of its mass by mixture with air alone, thus rendering, by the use of such heavy or low grade hydrocarbon, an exceedingly cheap fuel for power-production.

The novel construction of atomizing and mixing valve for combining to best advantage the three fuel-elements above-mentioned comprises, a tubular valve-body 1 provided with an exteriorly threaded extension 2, which is adapted to screw into a suitably threaded aperture in the walls 3 of the cylinder-chamber 4, and thus operatively connects said valve-mechanism with the engine-cylinder. Said valve-body 1 and its extension 2 are provided with an inwardly extending tubular opening 5 which terminates at its outlet-end in a conical seat-portion 6 formed by the inclined walls at the terminus of said tubular opening, and communicating with said tubular opening is an outlet passage 7, the flared mouth 8 of which opens directly into the said cylinder-chamber 4. Said tubular opening 5 is open at the outer end of said valve-body 1 so as to receive a movable valve-member 9 which penetrates into and is slidably arranged within said tubular opening. Said movable valve-body 9 is provided at its inner end with a conical head 10 which is adapted to be received upon said conical seat-portion 6, when the valve-mechanism is in its closed position. The outer end of said valve-body 1 is provided with a receiving socket or chamber 11 of greater diameter than the diameter of said movable valve-member 9, so that a suitable packing material 12 may be packed around said movable valve-member 9 to prevent leakage of the fuel-elements at the point of entrance of said movable valve-member into said valve-body. Said receiving socket or chamber 11 is interiorly threaded so that a suitable gland 13 may be screwed home to hold said packing material properly in place. The outwardly projecting end of said movable valve-member 9 is provided with a flanged collar 14, secured thereto in any suitable manner. Extending outwardly from said valve-body 1, and preferably forming an integral part thereof, is a bracket-arm 15 terminating in perforated ears 16 which support the fulcrum-pin 17 of a bell-crank lever 18 mounted upon the latter. The upwardly extending arm of said bell-crank lever 18 terminates in a forked portion 19 which straddles said flanged collar 14, and the free ends 20 of which are in operative engagement with said flanges of said flanged collar. Connected with the other arm of said bell-crank lever 18, by means of a forked connecting piece 21, is a connecting rod 22. The vertical movements of said connecting rod, which may be enforced by any well-known cam-movement operated and timed in connection with the

crank-shaft of the engine, operates said bell-crank lever 18 to produce the reciprocating or sliding movements of said movable valve-member 9 within said valve-body 1, to cause the properly timed opening and closing movements of the valve-mechanism, governed in accordance with the movement of the piston 23 within the cylinder-chamber 4, as will be readily understood. Said movable valve-member 9 is provided with a longitudinal groove or channel *a* which is engaged by a key or spline *B* secured in the said valve-body 1, thus permitting the longitudinal sliding movement of said valve-member, but preventing any twisting or turning of the same on its longitudinal axis, so that its proper related position with the said valve-body is always maintained. The said movable valve-member 9 is provided with a tubular passage or duct 24 which extends longitudinally and inwardly from its inner end to a suitable distance, said passage or duct 24 being closed by a suitable plug or closer 25. The said passage or duct 24 provides a mixing chamber for the reception of the several fuel-elements. Extending inwardly from the outer surfaces of said conical head 10 of said valve-member 9 are a plurality of radiating spray-ducts 26 which communicate with said passage or duct 24. When said conical head 10 of said valve-member 9 is normally seated upon said conical seat 6, viz., when the valve-member 9 is in its closed position, the outlet mouths of said spray-ducts 26 are closed by the contact with said conical seat 6. Connecting with the inner end of said passage or duct 24 are a series of radiating inlet-passages, namely, a hydrocarbon passage 27, a water passage 27' and an air passage 27'', all of which extend outwardly to the outer surface of said movable valve-member 9. Said valve-body 1 is also provided with a series of radiating extensions or bosses 28 each being provided with an intake-passage, one having a hydrocarbon intake-passage 29, another a water intake-passage 29', and another an air intake-passage 29''. The outer ends of said intake-passages are interiorly threaded for the reception of suitable delivery pipes 30, 30' and 30'' adapted to convey the several fuel-elements to said intake-passages.

The novel valve mechanism, thus above described in detail, operates as follows:—At proper times through the operation of the bell-crank lever 18 upon the movable valve-member 9, in the manner above indicated, said valve-member 9 is drawn outwardly until its several inlet passages 27, 27', and 27'' register respectively with the intake passages 29, 29' and 29'' of the valve body 1, and this movement also unseats the conical head 10 from the conical seat 6, and thus opens the spray ducts 26, in the manner in-

dicated in Fig. 2 of the accompanying drawings. This operation of the movable valve-member 9 thus opens the valve mechanism and prepares the same for receiving, mixing and atomizing and consequently delivering the proper fuel charge to the cylinder chamber 4. The several fuel elements are now impelled by suitable pumping mechanism through their respective delivery pipes 13 30, 30' and 30" into the intake passages of the valve-body 1 and through the inlet passages of the movable valve member 9 into the mixing chamber formed by the passage or duct 24. The impelled streams of hydrocarbon, 15 water and air passing through their respective passages and into the mixing chamber of the movable valve-member impinge upon each other and are thoroughly intermixed together, and in such intermixed condition 20 are expelled from said mixing chamber with atomizing effect through said spray ducts 26, the direction of which causes the atomized streams to again impinge upon the inclined surface of said conical seat 6 from 25 which they rebound in more thoroughly subdivided particles or oil coated globules of water, finally being expelled through the outlet passage 7 into the cylinder chamber 4, where the mixture thus delivered after being 30 compressed by the rising piston 23, comes in contact with the hot tube 31 communicating with the cylinder chamber 4, and is thereupon exploded, driving downwardly the piston 23 to produce its power stroke. In the 35 meantime a reversed movement of the bell-crank lever 18 has returned the movable valve-member 9 to its normal initial position, thus closing the valve-mechanism against the entrance of the fuel elements, and 40 shutting off the delivery openings thereof.

The extreme simplicity, both of construction and operation of the novel mixing and atomizing valve above described, will be apparent, the moving parts are greatly simplified in construction, and the chance of dis- 45 arrangement considerably minimized, at the same time the directness of its fuel passages, and the positiveness of its cut-off when in closed position, renders the mechanism little liable to choke through the collection of dirt or foreign particles carried in the fuel elements, or otherwise caused.

I am aware that changes may be made in the various arrangements and combinations 55 of the several devices and parts and in the features of my present invention without departing from the scope thereof, as described in the foregoing specification, and as defined in the claims appended thereto. Hence, I 60 do not limit my invention to the exact arrangements and combinations of the various devices and parts as herein set forth, and as illustrated in the accompanying drawings, nor do I confine myself to the exact details 95 of the construction of the said parts.

I claim:—

1. In a device of the character described, a valve body having an outlet passage and having a hydro-carbon intake passage, a water intake passage, and an air intake passage, a movable valve member slidably arranged within said valve body, said valve member being provided with a mixing chamber having a hydrocarbon inlet passage, a water inlet passage and an air inlet 70 passage which when registered with the corresponding intake passages of said valve body permit the entering streams of fuel elements to impinge upon each other within said mixing chamber, and said valve member being further provided at its head with a plurality of spray-ducts radiating from said mixing chamber and adapted to communicate with said outlet passage of said valve body. 75

2. In a device of the character described, a valve body having an outlet passage and having a hydrocarbon intake passage, a water intake passage, and an air intake passage, a movable valve member slidably arranged within said valve body, said valve member being provided with a mixing chamber having a hydrocarbon inlet passage, a water inlet passage and an air inlet 80 passage which when registered with the corresponding intake passages of said valve body permit the entering streams of fuel elements to impinge upon each other within said mixing chamber, and said valve member being further provided at its head with a plurality of spray-ducts radiating from said mixing chamber and adapted to communicate with said outlet passage of said valve body. 85

3. In a device of the character described, a valve body having a longitudinal chamber provided with a restricted outlet passage, said valve-body being further provided with a hydrocarbon intake passage, a water intake passage, and an air intake passage, a movable valve member slidably arranged within said longitudinal chamber of 90 said valve body, said valve member having a hydrocarbon inlet passage, a water inlet passage and an air inlet passage communicating with said mixing chamber of said valve-member, said valve-member being further 95 provided with a hydrocarbon inlet passage, a water inlet passage and an air inlet passage communicating with said mixing chamber of said valve-member, said valve-member being further 100 provided with a hydrocarbon inlet passage, a water inlet passage and an air inlet passage communicating with said mixing chamber of said valve-member, and means connected with said valve body for closing said spray ducts 105 when said valve member is in its closed position. 110

3. In a device of the character described, a valve body having a longitudinal chamber provided with a restricted outlet passage, said valve-body being further provided with a hydrocarbon intake passage, a water intake passage, and an air intake passage, a movable valve member slidably arranged within said longitudinal chamber of 115 said valve body, said valve member having a longitudinally extending mixing chamber, a conical head at one end of said valve-member, a conical seat at the end of said longitudinal chamber of said valve-body 120 adjacent to said restricted outlet thereof, said conical head having a plurality of radially disposed spray-ducts communicating with said mixing chamber of said valve-member, said valve-member being further 125 provided with a hydrocarbon inlet passage, a water inlet passage and an air inlet passage communicating with said mixing chamber of said valve-member, and adapted to be registered with said respective intake passages of said valve- 130

body, and means for longitudinally moving said valve-member to register its inlet passages with said intake passages of said valve-body and also to open its spray ducts in communication with said outlet passage of said valve-body.

4. In a device of the character described, a valve body provided with radiating intake passages and an outlet passage, a movable valve-member provided with a mixing chamber having radiating inlet passages adapted to be brought in registration with said intake passages of said valve body, a head formed on said valve-member, a plurality of spray ducts in the head of said

valve-member, a seat formed in said valve-body for receiving said head of said valve member so as to close said spray-ducts against communication with said outlet passage of said valve body, and means for 20 slidably reciprocating said valve-member within said valve-body.

In testimony, that I claim the invention set forth above I have hereunto set my hand this eighteenth day of May 1912.

WILSON D. CRAIG WRIGHT.
